UNITED STATES PATENT OFFICE.

JACOB NEGLEY, OF FAIRVIEW, ILLINOIS.

IMPROVEMENT IN WATER-ELEVATORS.

Specification forming part of Letters Patent No. 44,334, dated September 20, 1864.

To all whom it may concern:

Be it known that I, JACOB NEGLEY, of Fairview, in the county of Fulton and State of Illinois, have invented a new and Improved Water-Elevator; and I do hereby declare that the following is a full, clear, and exact description of the same, reference being had to the accompanying drawings, forming a part of this specification, in which—

Figure 1 represents a side elevation of my invention. Fig. 2 is a plan or top view of the same.

Similar letters of reference indicate corresponding parts in the two figures.

This invention consists in the combination, with a clock-movement, of an endless chain of buckets descending into a well or reservoir containing water and passing down in close proximity to a suitable reservoir in such a manner that by the action of said clock-movement motion is imparted the endless chain of buckets, causing the empty buckets to descend into the water, and, when full, to ascend and discharge their contents in the receiving-vessel, and that by these means a continuous raising of water from the well or reservoir is effected, without requiring any labor or attention except the occasional winding up of the clock.

A represents the frame, which forms the bearings for the several arbors of the clock-movement. This frame may be made of metal or any other suitable material, and it is secured to the platform or bed-plate B, which is situated over the well or reservoir from which the water is to be elevated. The clock-movement is similar to that of an ordinary eight-day clock, or it may be constructed in any desirable manner, and it may be driven by a weight or spring. If a weight is used, which in practice will be the most convenient, said weight is secured to a cord, a, which winds on a drum, b, secured to the arbor c of the clock-movement, and thence it may either hang down through a hole, d, in the platform B into the well, or the cord may be run up over a pulley arranged at a suitable height from the ground, and then down to get the requisite amount of motion for the weight. A suitable train of wheels transmits the motion from the arbor c to the arbor d, which carries the es-

capement-wheel e, and to which a drum, f, is secured, as clearly shown in Fig. 2 of the drawings. From the platform B extend two arms, g, down into the well or reservoir to such a depth below the surface of the water as will be necessary for the purpose of enabling the buckets to fill, and these arms form the bearings for the arbor h of the drum i. C is the endless chain of buckets, which is stretched over the drum f i, as clearly shown in Fig. 1 of the drawings, and this chain carries a series of buckets, j, each provided with an oblique spout, k, to discharge the contents of the same into the receiving spout or vessel l. This spout or vessel is so situated that the buckets pass down in close proximity to it, and that the same catches the contents of said buckets with the least possible waste or spilling. The motion imparted to the arbor d by the clock-movement takes place in the direction of the arrow marked near it in Fig. 1, and by this motion the empty buckets are carried down into the well and caused to dip into the receiver l, as indicated by arrows in Fig. 1.

The quantity of water elevated by this machine naturally depends upon the size of the buckets, the velocity of the motion of the chain, and finally upon the heft of the weight or power of the spring acting on the driving-shaft c and upon the number and proportion of the gear-wheels transmitting the motion from the driving-shaft to the shaft d, carrying the drum f. It is obvious, however, that the weight or spring can be readily so arranged in proportion to the number and size of the buckets that the requisite motion will be imparted to the endless chain C, and by the action of the buckets the operation of elevating water is continued without interruption as long as the clock continues to move.

What I claim as new, and desire to secure by Letters Patent, is—

The combination of an endless chain of buckets with a clock-movement and with a receiver, l, constructed and operating in the manner and for the purpose substantially as herein shown and described.

JACOB NEGLEY.
